MOUNTING FOR FRAGILE FINIALS

Arthur Koch, Ozone Park, N. Y., assignor to The
Little-Jones Company, Inc., New York, N. Y.

Application March 19, 1941, Serial No. 384,037

2 Claims. (Cl. 41—16.5)

This invention relates to finials in general and to fragile lamp-finials in particular.

Lamp-shades are frequently supported by means of arms forming a central eye. The latter is passed over a threaded bolt projecting from the lamp-post. The shade is secured to the lamp by means of a nut which engages the threaded bolt.

The taste of the trade and the commands of fashion make it necessary to adorn the shade-securing nut so as to form an ornamental finial. Thin, wafer-like disks carved out of fragile soap-stone and the like are appreciated ornaments for lamp finials.

These delicate soap-stone finials present special problems. The soap-stone ornament being much larger than the nut to which it is secured, presents a natural handle. Experience has shown that most persons instinctively grip the large soap-stone ornament when fastening the finial nut to the lamp. As a result, the delicate ornaments of soap-stone or the like are frequently broken or wrenched off the nut.

Breakage is often caused while "straightening" the ornament. After the nut has been turned all the way down on its bolt, it often happens that the ornament carried by the nut does not face straight forward. Attempts to straighten the ornament almost invariably result in breakage due to the inability of the nut to turn beyond the last thread on the supporting bolt. The present invention overcomes these disadvantages and produces several improvements as will become apparent from the following description.

The preferred embodiment of my invention is shown, by way of example, in the accompanying drawing, in which—

Fig. 1 is a perspective view of the finial nut;

Fig. 2 is a sectional view on line 2—2 of Fig. 1;

Fig. 3 is a sectional view of the finial nut before its assembly;

Fig. 4 illustrates the fastening means used for securing the ornament to the nut; and

Fig. 5 shows the finished finial as affixed to a lamp.

The finial according to the present invention comprises the locking element or nut 10 and ornamental disk 11, consisting for instance of delicately carved soap-stone. Element 10 consists of a lower part 12 and an upper carrier part 13. Part 12 is provided with a threaded bore 14 at its lower end and a peripheral rim 15 at its upper end. The carrier part 13 supports the ornamental disk 11. Carrier part 13 is rotatably

supported in cavity 16 formed by rim 15. Part 13 is held in position by the inwardly turned rim 15 as shown in Figs. 2 and 4. In order to lessen the friction between the bottom surface of carrier 13 and the bottom of cavity 16, the carrier 13 is provided with a central depression 17. Due to this construction, carrier 13 rests in the cavity 16 only on the annular rim 18. On its outside, part 12 is provided with three annular projections 19 which are knurled to afford a convenient grip when securing the finial to the lamp post.

Nut element 10 may be assembled as shown in Fig. 3. Rim 15 of part 12 is first given an upright position to permit insertion of carrier element 13. After the latter element is in place, rim 15 is turned inwardly on a lathe or otherwise, in order to permanently connect parts 12 and 13. Part 13 is thus freely rotatably mounted in part 12.

Ornamental disk 11 is provided with an aperture 20 through which wire 21 is threaded. The free ends of wire 21 are twisted together and inserted into cavity 22 of carrier element 13 where they are affixed by soldering or the like in the position shown in Fig. 4. A small heap of solder 23 is deposited in cavity 22 and about wire 21 on both sides of disk 11, right up to aperture 20, to firmly secure disk 11 to carrier 13. Due to this construction, the fragile disk 11 may be turned freely with respect to the lower part 12 of nut element 10. Cavity 22 is preferably so dimensioned that the lower part of disk 11 projects into the same. This mounting gives additional strength to the finial. If desired, the interconnected nut element 10 and ornamental disk 11 may be placed in a gold plating bath to give the solder and all other metallic parts a final finish.

Fig. 5 shows the finished finial fastened to lamp 24 which is supported on lamp-post 25. At the top of lamp-post 25, a threaded bolt 26 is provided which projects through ring 27. The latter carries shade 28 by means of arms 29. Shade 28 is securely held in place on lamp-post 25 by the nut element 10 of the finial. A reduction element 30 may be inserted in bore 14 of nut element 10 as shown in Fig. 2.

The finial is fastened to the lamp, by gripping the knurled surfaces 19, inserting the threaded bolt 26 into the threaded bore 14 of nut element 10 and screwing the same together.

The knurled rings 19 present a clearly recognizable grip. If a person nevertheless grips the fragile, ornamental disk 11 of soap-stone or the

like, the same will turn with respect to element 12 without injury. After the finial has been fastened to the lamp, it is possible to turn the ornamental disk to make it face in any direction desired without turning the nut or disturbing the lamp.

I claim:

1. A lamp finial comprising, in combination, a relatively fragile ornament, a carrier provided with a depression, a wire extending through an aperture in said ornament, the free ends of said wire being twisted together, the twisted ends of the wire being disposed in said depression and soldered to said carrier, said fragile ornament forming a rigid part of said carrier, a locking element provided with knurled, external gripping means and a threaded bore at one end, said locking element being provided with a rim at the opposite end, said carrier being disposed in the cavity formed by said rim on said locking element, said carrier being provided with a peripheral con-

striction to permanently interconnect said carrier and locking element, said carrier, being freely rotatable with respect to said locking element, the latter serving as a nut adapted to engage a threaded bolt on the lamp to which the finial is to be attached, whereby, when the fragile ornament is turned, the carrier is moved along and revolves jointly with the fragile ornament relative to the said locking element which is subjected to no torque on movement of said fragile ornament.

2. The device claimed in claim 1, in which said carrier is provided with a peripheral ring at its bottom surface to reduce the frictional contact between the carrier and the locking element and said depression in the carrier is of predetermined dimension in relation to said fragile ornament, the latter projecting into said depression, whereby a firm connection between the fragile ornament and said carrier is produced.

ARTHUR KOCH.
